UNITED STATES PATENT OFFICE.

RAPHAEL A. DE ROME, OF CHICAGO, ILLINOIS.

ARTIFICIAL TOOTH.

Application filed March 23, 1922. Serial No. 546,212.

To all whom it may concern:

Be it known that I, RAPHAEL A. DE ROME, a citizen of the United States, and a resident of Chicago, Cook County, and State of Illinois, have invented certain new and useful Improvements in Artificial Teeth, of which the following is declared to be a full, clear, and exact description.

This invention relates to artificial teeth and its principal object is to provide a novel, simple and efficient bicuspid and molar tooth for use in dental crown work and bridge work. Another object is to provide an artificial tooth structure comprising a porcelain facing or cusp and a backing arranged to be secured together by novel means and both parts being readily interchangeable, whereby in case a facing or cusp becomes broken, it may be readily replaced by a whole one. This invention has particular reference to bicuspids and molars and it has been designed for especial use in connection with facings constructed of porcelain or similar material. The invention consists in the several novel features hereinafter fully set forth and claimed.

The invention is clearly illustrated in the drawing accompanying this specification, in which:

Fig. 1 is a side elevation of an artificial tooth embodying a simple form of the present invention; Fig. 2 is a rear view thereof, looking in the direction of the arrow 2 in Fig. 1; Fig. 3 is a rear view of the facing 10 alone; Fig. 4 is an end view of the tooth, looking in the direction of the arrow 4 in Fig. 2; Fig. 5 is a vertical cross-section taken on the line 5—5 of Fig. 2; Fig. 6 is a plan, illustrating a blank from which one form of a backing is made, and Fig. 7 is a vertical cross-section taken through a backing constructed from the blank illustrated in Fig. 6.

Referring to said drawing, the reference character 10 designates the facing or cusp and 11 the backing of an artificial tooth structure, constructed in accordance with the present invention and secured together as hereinafter described. The tooth illustrated is one of the molar teeth but the invention is equally applicable to a bicuspid tooth.

On its lingual side, the facing 10 is formed with two flat, angularly disposed, intersecting faces 12, 13, which form an obtuse angle, one face 12 extending from its place of intersection with the face 13, to the gingival end of the tooth and the face 13 extending

from its place of intersection with the face 12 to the lingual side of the cusp 14. At the intersecting point between the two faces 12, 13, a recess or groove 15 is formed, which provides a continuation of the face 13 past the intersection of the two faces 12, 13. Extending back from the face 13, at a place adjacent the groove 15 is a flat, narrow recess or socket 16, the open end of which is parallel with the groove 15 and said recess or socket extends in an oblique or diagonal plane toward the buccal side of the cusp 14, thereby leaving an acute angle between the part 17 of the face 13 and the recess 16. The side walls of the recess are preferably flat and parallel.

The backing 11 is preferably formed of gold or precious metal and is in the form of a plate or sheet 18 one face 18^a of which is flat and lies contiguous with the face 13 of the facing 10. One edge portion of the plate or sheet 18 projects into the groove 15, and seats therein and its other marginal portions are bent around the sides of the cusp portion 17 of the facing to form a flange 19. Projecting from the face 18^a of the backing 11 is an inclined tongue or lug 20, which fits in and is seated and secured in the recess or socket 16. The facing 10 and backing 11 are secured together, when finally assembled, by cement, as is well understood.

The flanged marginal portions 19 may be made considerably thinner than the portion adjacent the tongue and the edge portion 90 which enters the groove, which permits said thinner marginal portions to be burnished against the sides of the tooth facing so as to obtain a close fit between the flange and facing.

While the backing and its tongue may be formed in various ways, a convenient and effective form is obtained by providing a blank such as is seen in Fig. 6, the body portion of which is slightly larger than the face 13 of the facing, so as to leave a considerable margin projecting beyond the facing. This margin or edge portion can be readily trimmed to correspond to the shape and size of the face 13. Projecting back from the straight side 18^b of the body portion 18 is an elongated tongue portion 20^a. A transverse slot 18^c is formed in the body portion, and the marginal portion may be slotted, as shown, to facilitate the work of bending up and burnishing the marginal portions against the facing. To form the backing,

the backing blank is folded along a line 18^a, which is parallel with and adjacent the straight edge 18^b and the tongue 20^a is folded along the lines, 20^b, 20^c, which provides the 5 tongue proper 20, and said tongue is thrust through the slot 18^c. The body portion and the part 20^a of the tongue portion and edge portion 18^c are folded tightly together and secured together by solder or otherwise. The 10 tongue is bent to stand at the proper angle to the body portion and the marginal portions (which are to be bent up) are rolled down hammered down to thin them out toward their edges. Doubling the tongue portion 15 upon itself and upon the body portion doubles the thickness of the material at the places where strength is required, leaving the outer portions free to be thinned down at the margins where thinness of material is required.

From the above, it is obvious that only a few standard sizes of backings are required to accommodate bicuspid and molar teeth, and that by trimming off the edges of the 25 backings, they may be made to accommodate the various sizes and shapes of bicuspid and molar teeth. This dispenses with the necessity of keeping a great variety of sizes and shapes in stock, and dispenses with the necessity of providing a great many tools and dies 30 for blanking out a great multiplicity of sizes and shapes.

By the term "facing" is meant the porcelain portion of a bicuspid or molar artificial tooth which embraces the buccal and occlusal sides of the tooth structure.

More or less variation of the exact details of construction of this invention is possible without departing from the spirit of this invention; I desire, therefore, not to limit myself to the exact form of the construction shown and described, but intend in the following claims to point out all of the invention disclosed herein.

45 I claim as new and desire to secure by Letters Patent:

1. An artificial tooth structure, comprising a facing and a metal backing, the facing being formed with two flat angularly disposed, 50 intersecting faces on its lingual side, one face of which extends in a plane slightly inclined with respect to the occlusal side of the facing, there being a recess extending back from said last mentioned face, and 55 there being a recess in said facing at the place of intersection between said faces disposed at an angle with respect to said first mentioned recess, and said backing being arranged to lie against said last mentioned 60 face and having angularly disposed portions entering both of said recesses and acting to prevent accidental disconnection between the facing and backing.

2. An artificial tooth structure, comprising

ing a facing and a metal backing, the facing 65 being formed with two flat angularly disposed, intersecting faces on its lingual side, one face of which extends in a plane slightly inclined with respect to the occlusal side of the facing, there being a recess extending 70 back from said last mentioned face, and there being a recess in said facing at the place of intersection between said faces disposed at an angle with respect to said first mentioned recess, and said backing being arranged to 75 lie against said last mentioned face and having a tongue arranged to enter said first mentioned recess, and an edge portion arranged to snap into said second named recess, whereby the facing and backing are 80 prevented from accidental disconnection.

3. An artificial tooth structure, comprising a facing and a metal backing, the facing being formed with two flat angularly disposed, 85 intersecting faces on its lingual side, one face of which extends transversely of the facing, there being a recess in the body of the facing extending back from said transverse face, and a transverse groove at the end of said transverse face which intersects 90 with the other face, and said backing being arranged to lie against said transverse face with one end portion seated in said groove, and having a tongue extending into said recess in the facing.

4. An artificial tooth structure, comprising a facing and a metal backing, the facing being formed with two flat angularly disposed, intersecting faces on its lingual side, one face of which extends transversely of the 100 facing, there being a recess in the body of the facing extending back from said transverse face, and a transverse groove at the end of said transverse face which intersects with the other face, and said backing being 105 arranged to lie against said transverse face with one end portion seated in said groove, and having a tongue extending into said recess in the facing, the exposed marginal portion of the backing being burnished around 110 the adjacent sides of the tooth.

5. An artificial tooth structure, comprising a facing and a metal backing, the facing being formed with two flat angularly disposed, 115 intersecting faces on its lingual side, one face of which extends transversely of the facing, there being a recess in the body of the facing extending back from said transverse face, and a transverse groove at the end of said transverse face which intersects 120 with the other face, and said backing being arranged to lie against said transverse face with one end portion seated in said groove, and having a tongue extending into said recess in the facing, the other edge portion of 125 the plate being thinner than the middle portion thereof.

RAPHAEL A. DE ROME.
